CENTRIFUGAL PUMP

Francis E. Brady, Jr., Richmond, Ind., assignor,
by mesne assignments, to Richmond Turbine
Pump Co. Inc., Richmond, Ind.

Application August 11, 1932, Serial No. 629,019

17 Claims. (CL. 103—96)

My invention relates to hydraulic pumping apparatus.

The pump of my invention is a regenerative pump in which the runner bucket impinges 5 against the free fluid in the channel of the pump and carries the fluid therein with it, a plurality of such buckets engaging the fluid in the channel.

My pump does not depend upon centrifugal 10 effect upon the water, it does not utilize centrifugal force as its prime motive power, and it does not depend upon the velocity of the water as built up by the impeller and upon means for changing this velocity into pressure.

15 It is my object to eliminate the movement of the fluid between impeller vanes.

It is the object of my invention to place my 20 vanes on the peripheral side of the impeller and pocket them so that any centrifugal force will actually work against the impeller.

25 It is my object to provide an impeller in which the vanes are inclined in the direction of movement of the fluid so that centrifugal movement of the fluid upwardly will be against the overhanging sides of the vanes, thereby materially increasing the head of the pump.

It is my object to so form the rear side of the 30 runner vanes in a true relief curve that I decrease the torque without losing an increase in working efficiency of the pump.

It is my object to provide a pump which is capable of pumping against higher pressure for a given peripheral speed than is possible with 35 centrifugal impeller pumps.

40 It is my object to provide a circumferential taper of approximately 15 degrees to hold a running clearance in this type of pump.

It is my object to provide a runner vane in 45 which the depth of the vane should be equal to the depth of the channel carrying the stream of fluid and the vane shall face the fluid in the direction of rotation at an angle of about 45 degrees to the tangent of its point of contact with the periphery.

45 It is desirable that the space between the vanes shall be 1½ times their depth along the vane face and that the rear side of the vane shall slope backwardly to the base of the vane behind it giving full relief to the flow of water to prevent turbulence behind each vane.

Referring to the drawings:

Figure 1 is a side elevation of the pump partially in section with the cover plate partially broken away;

Figure 2 is a section on the line 2—2 of Figure 1; Figure 3 is a top plan view of the impeller;

Figure 4 is a similar view to Figure 1 with a modified form of impeller vane;

Figure 5 is a section on the line 5—5 of Figure 4; 60

Figure 6 is a section on the line 6—6 of Figure 4;

Figure 7 is a top plan view of a portion of the modified form of impeller vanes.

Referring to the drawings in detail, 1 indicates a conventional base for a pump casing, which has 65 an inlet passageway 2 communicating with a rotor chamber port 3. This chamber has an outlet port 4 communicating with a discharge passageway 5. A rotor chamber 6 is formed by one

side of the casing 7 and a detachable cover plate 70 8 held in position by the bolts 9. The wall 7 is provided with a bearing sleeve 10 having a bearing 11 for supporting the rotor shaft 12. Between the rotor 13 and the interior of the bearing 11 is a packing gland 14 held in position by the spring 75

15. The other end of the shaft 12 has threaded thereon a bearing member 15a which rides against a ball 16 that in turn rests upon the screw member 17 carried in the sleeve 18 and the detachable cover plate 8. This member 17 is adjusted 80 through the socket 19 and lock nut 20.

It will be noted that the cover plate 8 is provided with a tapered flange 21 having a tapered surface 22 in which is cut a fluid channel 23. Cooperating with this taper is a tapered surface 85 24 of the impeller in which is a peripheral channel 25 divided transversely by a plurality of overhanging teeth 26 preferably formed and arranged as heretofore described.

Turning to the form shown in Figures 4, 5, 6 90 and 7, it will be noted that the impeller, instead of having a water channel between oppositely-disposed shoulders 25a and 25b, has only the single shoulder 25a. The teeth in this connection of the impeller form the vanes. 95

It will be understood that I desire to comprehend within my invention such modifications as may be necessary to adapt it to varying conditions and uses.

Having thus fully described my invention, what 100 I claim as new and desire to secure by Letters Patent, is:—

1. In a pump, a pump casing having a tangential inlet passageway and a radial outlet passageway, a closure plate for the casing having 105 a flange forming an annular water passageway extending substantially around the inside of the casing and communicating with the inlet passageway and the outlet passageway, and a rotary impeller mounted within said flange and forming a 110

- portion of the wall of said annular passageway, said flange surrounding the impeller and located between it and the inner annular wall of the casing, said impeller having a plurality of spaced 5 teeth inclined in the direction of rotation of the impeller from the inlet to the outlet passageway.
2. In a pump, a pump casing having a tangential inlet passageway and a radial outlet passageway, a closure plate for the casing having a flange 10 forming an annular water passageway extending substantially around the inside of the casing and communicating with the inlet passageway and the outlet passageway, and a rotary impeller mounted within said flange and forming a portion of the wall of said annular passageway, said flange surrounding the impeller and located 15 between it and the inner annular wall of the casing, said impeller having a plurality of spaced teeth inclined in the direction of rotation of the impeller from the inlet to the outlet passageway, said teeth having on one side at least a wall 20 of the impeller.
3. In a pump, a pump casing having a tangential inlet passageway and a radial outlet passageway, a closure plate for the casing having a flange 25 forming an annular water passageway extending substantially around the inside of the casing and communicating with the inlet passageway and the outlet passageway, and a rotary impeller mounted within said flange and forming a portion 30 of the wall of said annular passageway, said flange surrounding the impeller and located between it and the inner annular wall of the casing, said impeller having a plurality of spaced teeth inclined in the direction of rotation of the impeller from the inlet to the outlet passageway, said teeth having opposite side walls to form a channel therebetween in which the teeth are located 35 and across which they extend.
4. In a pump, a pump casing having a tangential inlet passageway and a radial outlet passageway, a closure plate for the casing having a flange 40 forming an annular water passageway extending substantially around the inside of the casing and communicating with the inlet passageway and the outlet passageway, and a rotary impeller mounted within said flange and forming a portion of the wall of said annular passageway, said impeller having a plurality of spaced teeth inclined in the 45 direction of rotation of the impeller from the inlet to the outlet passageway, said teeth having opposite side walls to form a channel therebetween, in which the teeth are located and across which they extend, the exterior of said impeller 50 and its teeth having a conical form cooperating with an interiorly-disposed conical surface of the pump casing with which it forms the annular water passageway.
5. In a pump, a casing having in one side a 55 rotor chamber with an inlet and outlet port, a relatively shallow rotary impeller disk in said chamber having a plurality of peripherally-arranged teeth annularly disposed and inclined in the direction of rotation of the impeller and a cover plate for said chamber having an annular flange extending therein and located between the outer periphery of the impeller and an inner annular wall of said chamber.
6. In a pump, a casing having in one side a 60 rotor chamber within inlet and outlet port, a relatively shallow rotary impeller disk in said chamber having a plurality of peripherally-arranged teeth annularly disposed and inclined in the direction of rotation of the impeller, a cover plate for said chamber having a flange surround- 65
- ing the impeller disk, and an annular wall on the side of said teeth cooperating with said flange to form therewith a water passageway from the inlet to the outlet ports into which passageway said teeth project.
7. In a pump having a casing with an inlet port and outlet port at right angles to each other, a relatively shallow rotary impeller disk having a plurality of peripherally-arranged teeth annularly disposed and inclined in the direction of rotation of the impeller, an annular wall on the side of said teeth cooperating with said casing to form therewith a water passageway from the inlet to the outlet ports into which passageway said teeth project, said teeth having their outer faces inclined at an angle on an axis about which the impeller rotates, and a closure plate for the casing having a flange around the impeller disk, said flange having therein adjacent the disk a fluid channel connected to the inlet port and the outlet port.
8. In a pump, a pump casing having an inlet and exit passageway communicating with an annular chamber in said casing, a tapered flange 100 detachably mounted in said casing and carried by a cover plate mounted on said casing, and forming therewith said chamber, and an impeller traveling within said sleeve, said impeller having a plurality of teeth inclined in the direction of rotation thereof.
9. In a pump comprising means for forming an inlet passageway and an outlet passageway and an annular impeller chamber having an open face, means of supporting an impeller shaft extending from said face, an impeller mounted in said open space carrying an impeller shaft and a detachable cover member adapted to support the other end of the impeller shaft, close the open face of the pump casing and form with the periphery of the impeller an annular water chamber in communication with said inlet and outlet passageways, said impeller having a plurality of teeth inclined in the direction of rotation thereof extending into and partially across said annular water chamber, said impeller having a tapered external face and said portion of the cover having a cooperating tapered face whereby a seal is formed between the impeller and said casing to prevent leakage from said annular space for fluid, and yielding means between said impeller and the casing forcing the impeller against the cover.
10. In a pump, a casing having a horizontally-disposed bearing sleeve for an impeller shaft and a cup-shaped depression in the face thereof communicating with outlet and inlet passageways, a cover plate for said annular depression having a sleeve and a laterally-extending tapered flange around the sleeve adapted to form with an impeller an annular fluid passageway, an impeller having a cooperating peripherally-tapered face with inclined teeth on the periphery thereof extending into said annular passageway, an impeller shaft extending into and supported by the sleeve in said cover and the sleeve on the pump casing.
11. In a pump, a casing having a horizontally-disposed bearing sleeve for an impeller shaft and a cup-shaped depression in the face thereof communicating with outlet and inlet passageways, a cover plate for said annular depression having a sleeve and a laterally-extending tapered flange around the sleeve adapted to form with an impeller and annular fluid passageway, an impeller having a cooperating peripherally-tapered face

- with inclined teeth on the periphery thereof extending into said annular passageway, an impeller shaft extending into and supported by the sleeve in said cover and the sleeve on the pump casing, 5 yielding means for forcing said impeller peripherally against said cover, and an adjustable thrust means associated with said cover for receiving the thrust on the impeller and the shaft. 12. In a pump, a casing having a circular chamber with a cone-shaped periphery, a rotor in the chamber having a cone-shaped periphery engaging the periphery of the chamber, said casing having a passageway substantially around the periphery of the rotor, and means to adjust the 15 rotor in the chamber, said means including a screw and a spring acting against the screw. 13. In a pump, a casing forming a circular chamber and having bearing sleeves, a rotor in said chamber, a shaft for said rotor in said sleeves, 20 means in one sleeve to adjust the shaft and the rotor, and means in the other sleeve acting on the rotor against the adjusting means. 14. In a pump, a casing having a tangential inlet passageway, a radial discharge passageway 25 and an annular channel connecting said passageways, the surface of the casing in which the channel is located being conical, an impeller in the casing having a conical surface on its periphery engaging the conical surface of the casing, 30 teeth in the periphery of the impeller, and yielding means tending to hold said conical surfaces in engagement with each other. 15. In a pump, a casing having a tangential inlet passageway, a radial discharge passageway 35

- and an annular channel connecting said passageways, the surface of the casing in which the channel is located being conical, an impeller in the casing having a conical surface on its periphery engaging the conical surface of the casing, teeth in the periphery of the impeller, yielding means tending to hold said conical surfaces in engagement with each other, and means at each end of each of the teeth to form a sealing connection between the impeller and the casing on each side of the channel. 16. In a pump, a plate having an annular flange with a tapered inner surface, said inner surface having a fluid channel extending partly around the inside of the flange and terminating in an inlet and in an outlet through the flange, a rotor having a tapered periphery, said rotor entirely surrounded by said flange, and adapted to engage the tapered inner surface of the flange, and teeth formed in the periphery of the rotor adjacent the channel. 17. In a pump, a plate having an annular flange with a tapered inner surface, said inner surface having a fluid channel extending partly around the inside of the flange and terminating in an inlet and in an outlet through the flange, a rotor having a tapered periphery, said rotor entirely surrounded by said flange, and adapted to engage the tapered inner surface of the flange, teeth formed in the periphery of the rotor adjacent the channel, and a casing to support the plate and force the rotor against the flange. FRANCIS E. BRADY, JR.
